[57] **CLAIM**

The ornamental design of a combined remote control and cradle assembly for a ceiling fan and light fixture, as shown and described.

DESCRIPTION

FIG. 1 is a perspective view of a combined remote control and cradle assembly for a ceiling fan and light fixture showing my new design;

FIG. 2 is a front view of FIG. 1;

FIG. 3 is a right-side view of FIG. 1, with the left-side view of FIG. 1 being a mirror image of FIG. 3;

FIG. 4 is a rear view of FIG. 1;

FIG. 5 is a top view of FIG. 1; and,

FIG. 6 is a bottom view of FIG. 1.
